APPARATUS FOR PRINTING, SHEETS, FILMS OR LENGTHS OF MATERIAL, NOTABLY TEXTILE MATERIAL, BY MEANS OF SCREEN PRINTING

Robert Ronald Laupman, Wychen, Netherlands

Application May 1, 1952, Serial No. 285,512

Claims priority, application Netherlands May 2, 1951

3 Claims. (Cl. 101—126)

It has been tried to mechanize screen printing in two directions. On the one hand by mechanically performing the ordinary manual manipulations of printing on tables, on the other hand by passing the cloth on a belt beneath stationary screens in a special machine. If we regard this last method which couples an economization in space to a high output, we distinguish the following essential steps:

1. Putting down the screen
2. Placing the squeegee behind the printing paste
3. Passing the squeegee over the screen
4. Lifting the squeegee
5. Lifting the screen
6. Passing on the cloth

These steps are intermittent. In many ways it has been tried to mechanize these steps: electrically, with the help of contact rollers and relays, mechanically with the help of various cams, ratchet mechanisms, etc. However, owing to their being highly complicated the machines which mechanize the steps in question give rise to the danger that one of their parts will stall, so that misprints will result which can destroy an entire length of cloth.

Now it is an object of the present invention to carry out the said steps by means of a very simple apparatus, said steps being split up into two groups:

1. The steps synchronous with the passing on of the cloth;
2. The movement of the squeegee.

The apparatus according to the invention is based on a very simple principle, which, however, by its very simplicity, opens up very attractive perspectives from the points of view of construction and operation.

The new apparatus is characterized in that in the lifted position the squeegee performs an even number of inoperative strokes, starting just before the squeezed off printing paste and ending just behind said printing paste, to subsequently perform a number of operative strokes which number is smaller than the number of inoperative strokes.

A suitable embodiment comprises two rotating driving shafts or spindles, one of which periodically displaces the material to be printed, while the other shaft or spindle imparts a reciprocatory movement to a squeegee carrier, adapted to be lifted by means of a cam or cam disc, which is rotated by said first-named spindle, the screen being lifted by the same or by another cam or cam disc rotated by said spindle, the ratio between the numbers of revolutions of said spindles or shafts being $2: (4x-y)$, in which formula x and y represent integers which at least equal 1.

If only one cam disc is used, it is to be recommended that the part cooperating with this cam disc and lifting the squeegee carrier likewise cooperates with some play with the screen part to be lifted.

In order to enable the material to be printed to be passed on periodically it is of advantage if the first shaft rotates an arm the length of which is preferably adjustable, which arm drives a one-way coupling in opposition to a spring by means of a chain or a toothed rack, which

2

coupling periodically displaces the conveyor belt for the material to be printed.

If large lengths are to be printed, so that the size of the screen or screens is insufficient, it is possible, if more than one squeegee is used, to make the squeegees adjustable in vertical direction relatively to the squeegee carrier by means of a Jacquard mechanism.

This is also very suitable for obtaining a greater variation in the pattern.

The invention is further elucidated hereinafter with reference to the accompanying drawing.

In this drawing:

Fig. 1 is a diagrammatic side view of the screen printing machine;

Fig. 1a is a side view of the ends of the carrier belt for the material to be printed;

Fig. 2 on a larger scale shows a cross section taken on the line II—II in Fig. 1;

Fig. 3 is a fragmentary view of the cam disc for lifting and lowering the screen support and the squeegee-carrier;

Fig. 4 diagrammatically shows the movement of a squeegee between two subsequent working end positions;

Fig. 5 is a plan view of a number of screen frames, each provided with a printing screen;

Fig. 6 on a larger scale shows a cross section taken on the line VI—VI in Fig. 1.

Referring to the drawings, the screen printing machine comprises a main frame 1, which carries at its ends rollers 8 and 27 for supporting an endless belt 26 which is driven intermittently and adjustably to move the fabric 28 to be printed successively to the printing positions.

The fabric 28 is fed from a supply reel 29 and is secured to the belt by means of an adhesive. After the fabric 28 has been printed it leaves the exit end of the machine and is stripped from the belt 26 by a stripping knife 30.

The main frame 1 is further provided with a motor 2 for driving the shafts 4 and 10, which shafts are rotatably supported by the main frame 1 and which are each provided with a gear. The gears are interconnected with each other and with the motor 2 by a driving chain 3.

An arm 5 fixed to one end of the shaft 4 has an adjustable sleeve 6 thereon to which a cable 7 is secured, which cable is passed over a pulley of a one-way coupling on the roller 8. The other end of cable 7 is secured to a draw spring 9 which is fixed to the main frame 1.

During the rotation of the shaft 4, driven by the motor 2, the roller 8 together with the endless belt 26 and the fabric 28 is intermittently driven to advance the fabric 28 from one position to the next. The distance the belt moves on each stroke may be adjusted by adjusting the position of sleeve 6.

A framework composed of longitudinal rods 16 and 17 pivoted to each other at their adjacent ends at 18 and cross bars 22 and 24, is so suspended from the longitudinal walls of the main frame 1 that the two halves of said framework are adapted to oscillate about the shafts 20 and 21 respectively.

The framework carries rollers 25 at its two longitudinal sides, on which rollers a squeegee carrier 14 bears. A number of squeegees 34 are secured to the carrier by means of cross bars 33 and clamps 32. The squeegee carrier is adapted to travel over the rollers 25. The squeegee carrier 14 is provided with an arm 31 to which the one end of a connecting rod 13 is coupled. The other end is coupled by an adjustable sleeve 12 to an arm 11 secured to the shaft 10.

During the rotation of the shaft 10 which is driven by the motor 2, the squeegee carrier 14 is reciprocated over the rollers 25 by the connecting rod 13.

Within the space defined by the squeegee carrier 14 a

3

support for a number of screens is located. This screen support consists of a frame structure composed of longitudinal and transverse rods 41 and 40 and of auxiliary rods 43. The hooks 39 of supporting rods 38 are secured thereto by means of bolts 42. Said supporting rods 38 serve for securing thereto the screens, which screens consist of a metal frame 37 surrounded by a wooden framework 36 against the lower side of which a patterned piece of gauze 35 is secured.

The longitudinal rods 41 of the screen support are provided with vertically adjustable pins 15 and 23 which end at some distance above the cross bars 22 and 24 of the framework 16 and 17. The transverse rod 22 in the framework carries a roller 19, which bears on the circumference of a cam disc 46 secured to the shaft 4.

During the rotation of the shaft 4 and the cam disc 46, the roller 19 resting on the cam disc will lift the outer ends of the rods 16 and 17 upwardly and downwardly so that the squeegee carrier 14, supported on the rollers 25, together with the squeegees 34 is likewise moved upwardly and downwardly. During the upward movement of the outer ends of the rods 16 and 17 the ends thereof will contact the lower ends of the pins 23 and 15 and the screen support will be moved upwardly. During the downward movement of the outer ends of the rods 16 and 17 the screen support will follow this downward movement until the auxiliary rods 43 of the screen support come to a standstill by their running against the main frame 1. The lower ends of the pins 23 and 15 will no longer contact the levers 16 and 17 during the subsequent lowering of the squeegee carrier 14.

During the upward and downward movement of the squeegee carrier and the screen support and during the intervals between said upward and said downward movement the squeegee carrier 14 performs an uninterrupted reciprocatory movement over the rollers 25.

For timing said upward and downward and reciprocatory movements the chain gears secured to the shafts 4 and 10 are so constructed in the embodiment shown that the shaft 4 will perform two revolutions in the time during which the shaft 10 performs three revolutions, and the cam disc 46 secured to the shaft 4 has a circumferential shape as shown in Fig. 3.

As long as the roller 19 bears on the portion of the largest radius of the cam disc 46, the screen support and the squeegee carrier 14 will be lifted in the highest position so that they are free from the carrier belt 26 carrying the fabric 28. The belt 26 with the fabric 28 will be advanced by the rotating arm 5 and the cable 7 to a next printing position. All of this happens during a rotation of the cam disc 46 over the angle T_a .

After (in case of the cam disc 46 having the direction of rotation shown in Fig. 3) the radius J has passed the roller 19, the screen support and the squeegee carrier will start moving downwardly.

When the point of intersection of the circumference of the cam disc and the circle g passes the roller 19 the screen support has reached its lowest position and the screens (47, 48, 49, Fig. 5) will lie on the fabric 28.

When the point of intersection of the cam disc circumference and the radius k pass the roller 19 the squeegees 34 (which have meanwhile arrived again in their extreme left hand or, as shown in Fig. 4, right hand position) also will have reached their lowest position and have come to rest between the printing colour 45 present on the closed edge 50 of each screen and the associated screen frame 37.

When the cam disc 46 continues rotating, the printing colour 45 is pushed off said closed screen edge 50 by each squeegee (then moving to the left according to Fig. 4) during the time when the cam disc covers the angle between the radii k and l ; during the time when the cam disc covers the angle between the radii l and m the squeegees will push the printing colour 45 onto the opposite closed screen edge 50, and immediately

4

thereafter each squeegee 34 is lifted off the associated screen (the opposite stroke a of the squeegees according to Fig. 4).

During the time when the cam disc 46 covers the angle between the radii n and o the squeegee carrier 14 together with the squeegees 34 is lifted higher and also the screen support is moved upwardly.

After the screen support and the squeegee carrier 14 have reached their highest position, the advancement of the belt 26 with the fabric 28 to the next position starts.

During this advancement of the belt 26, which continues until the radius J of the cam disc 46 passes the roller 19 again, the squeegees 34 in their lifted position perform the inoperative strokes b and c which have already started in the meantime (Fig. 4). During the subsequent complete revolution of the cam disc 46 the squeegees 34 continue moving without coming to a standstill, for performing an operative stroke a and two inoperative strokes b and c , this time, however, according to the mirror image of Fig. 4, while during the operative stroke the printing colour 45 is pushed in opposite direction across the screen having the new portion of the fabric to be printed located thereunder. This continues as long as the cam disc 46 rotates.

According to the embodiment the belt 26 is periodically advanced over a distance e (Fig. 5) so that each printed portion of fabric 28 is advanced first to an intermediate position and subsequently to the next printing position.

Because during the operation of the screen printing machine the squeegee carrier 14 with the squeegees 34 continues moving, high printing speeds can be reached, while the chance of misprinting is minimized.

Although according to the embodiment described each squeegee performs two inoperative strokes in its lifted position, which strokes start just before the squeegee mass of printing colour and which end just behind said mass, whereupon each squeegee performs one operative stroke, it will be clear that a number of operative and a subsequent number of inoperative strokes of the squeegee or squeegees may be selected according to requirements, provided that the shape and the speed of revolution of the means for periodically driving the belt and for continuously driving the squeegee carrier, as well as the lifting and lowering of the squeegee carrier and the screen support be adapted thereto.

If the number of operative strokes is larger than 1, the cam disc must be provided with a corresponding number of cams to lift only the squeegee carrier. The screens then remain in their places.

The only possibility of the operation getting out of tune resides in the one way coupling. If however, the lengths of repeat are normalized to multiples of a given unit of length, this coupling can be replaced by a ratchet so that mistakes are excluded.

The construction described admits of very high printing speeds with a minimum chance of misprinting, because the possibility of one of the operations being skipped is excluded.

I claim:

1. A screen printing machine for sheets and lengths of textile, paper and the like, comprising a main frame, two rollers and two shafts rotatably mounted on said frame, an endless belt supported for movement on said rollers and adapted to carry the material to be printed, one of said rollers having a one-way driving pulley thereon, adjustable means for intermittently moving said belt mounted on the first of said two shafts and comprising an arm having an adjustable sleeve thereon and a spring tension cable attached at one end to said sleeve and passing around said one-way pulley and having the other end attached to said frame, a screen support mounted above the endless belt, a squeegee carrier mounted above the screen support and provided with a number of squeegees fixed to the carrier, means for continuously reciprocating the squeegee carrier mounted on said second shaft

and comprising an arm and a link pivotally connected to one end of said arm with the free end of said link pivotally connected to said squeegee carrier, means for periodically first lifting the squeegee carrier from the screen support and subsequently the spaced squeegee carrier and screen support from the endless belt and for first lowering the spaced squeegee carrier and screen support towards the endless belt and for subsequently lowering the squeegee carrier towards the screen support, said means for intermittently moving the endless belt being operable during the lifting of the squeegee carrier and the screen support, and means on said frame for driving the second shaft at least one and one-half times as fast as said first shaft and for driving said lifting means.

2. A screen printing machine for sheets and lengths of textile, paper and the like, comprising a main frame, an endless belt supported for movement on the main frame and adapted to carry the material to be printed, adjustable means for intermittently moving said belt, a screen support mounted above the endless belt, a squeegee carrier mounted above the screen support and provided with a number of squeegees fixed to the carrier, means for continuously reciprocating the squeegee carrier, means for periodically first lifting the squeegee carrier from the screen support and subsequently the spaced squeegee carrier and screen support from the endless belt and for first lowering the spaced squeegee carrier and screen support towards the endless belt and for subsequently lowering the squeegee carrier towards the screen support comprising a pair of levers pivoted at their centers to said frame in the longitudinal direction thereof and having their adjacent ends pivotally connected to each other, a pair of rollers mounted at the ends of said levers op-

posite said pivotal connection on which said squeegee carrier rolls, a follower wheel suspended from one end of said levers, pins adjustably mounted on said screen support over the ends of said levers opposite said pivotal connection and adjusted to contact the ends of said levers after said levers have been pivoted from the horizontal position, and cam means rotatably mounted on said frame contacting said follower wheel and adapted to urge said wheel upwardly to pivot said levers and thus lift said squeegee carrier and to continue to urge said wheel upwardly to bear against said pins and lift said screen support in timed relation to said means for moving said belt, said means for intermittently moving the endless belt being operable during the lifting of the squeegee carrier and the screen support, and means on said frame for driving said belt moving means, said reciprocating means and said lifting means.

3. A screen printing machine as claimed in claim 2 in which said cam means has a profile to lift the squeegee carrier from the screen support at the end of at least one operative stroke of the squeegee carrier and to lower the squeegee carrier toward the screen support at the end of at least two following inoperative strokes of the squeegee carrier.
